United States Patent Office

Des. 202,541
Patented Oct. 19, 1965

202,541

COT

Albert J. Borrelli, Stoneham, Mass., assignor to Verta-Aide Corp., Woburn, Mass., a corporation of Massachusetts

Filed Jan. 5, 1965, Ser. No. 83,274

Term of patent 14 years

(Cl. D5—4)

FIG. 1

FIG. 2

FIG. 3

FIG. 4

FIG. 5

FIGURE 1 is a perspective view of my cot, showing the body support portion thereof in the fully raised position;

FIGURE 2 is a perspective view of the cot, showing the body support portion thereof in the closed position;

FIGURE 3 is a side view of the cot, showing the body support portion thereof in the partially raised position;

FIGURE 4 is a fragmentary perspective view showing one end of the cot; and

FIGURE 5 is an exaggerated, fragmentary perspective view showing the other end.

I claim:

The ornamental design for a cot, substantially as shown.
